ATTORNEY

UNITED STATES PATENT OFFICE.

IRVING M. FLANAGAN, OF SCHENECTADY, NEW YORK.

SHADE-BRACKET.

1,082,939.

Specification of Letters Patent.

Patented Dec. 30, 1913.

Application filed February 19, 1912. Serial No. 678,629.

To all whom it may concern:

Be it known that I, IRVING M. FLANAGAN, a citizen of the United States, residing at Schenectady, county of Schenectady, and 5 State of New York, have invented certain new and useful Improvements in Shade-Brackets, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a horizontal section taken through my improved shade-20 fixture mounted upon a window-casing. Fig. 2 is a similar view showing the shade-roller bracket secured in the reversed position for use, and the attaching-bracket secured directly to the outer edge of the window-case molding. Fig. 3 is a view in perspective of the reversible shade-roller bracket detached. Fig. 4 is a view in perspective of the attaching-bracket-member which supports the shade-roller bracket. 25 Fig. 5 is a horizontal section taken through the attaching-bracket shown in Fig. 1, with the inner angle-plate in reversed position.

The principal object of the invention is to provide a shade-fixture having a bearing-bracket for the shade-roller which can be mounted in different positions upon window-casings of different cross-sectional forms to support the shade-roller in proper relation to the face of the window-casing.

40 Other objects will appear in connection with the following description.

Referring to the drawings wherein the invention is shown in preferred form, 1, represents the window-casing and, 2, a face-molding thereon.

The bearing-bracket, 3, which contains the bearings for the shade-roller, indicated by dotted lines, 4, is in the form of an angle-plate having a slotted shank, 5, adjustably 50 mounted by means of a thumb-screw, 6, upon an attaching-bracket shown in Fig. 1 as formed of an outer angle-plate, 7, and an inner angle-plate, 8, having mutually lapping end-members adjustably connected together by means of a thumb-screw, 9, passing 55 through a slot, 10, in one of the lapping

members at the outer edge of the window-case molding 2. The other members of the angular bracket-plates, 7 and 8, extend along the outer and inner faces, respectively, of the window-case molding, 2, embracing said molding between them. The inner angle-plate, 8, is secured directly to the frame of the window-casing by means of screws or 60 nails 11. The angle-plate, 8, can be thus attached to the frame of a window-casing before the molding, 2, is placed in position. The adjustment provided for by the slot, 10, adapts this bearing-bracket to embrace 65 window-case moldings of different thicknesses. 70

The bearing-bracket, 3, is reversible upon the attaching-bracket plate, 7, and is provided with a plurality of bearing-apertures, 13 and 14, each of which is adapted to receive the trunnion or spindle of an ordinary shade-roller. 75

In Fig. 1, I have shown the bearing-bracket, 3, mounted upon the attaching-bracket-plate, 7, with the bearing end of 80 said bracket projecting outward, in which position the outer bearing-aperture, 14, is adapted to receive the trunnion or spindle of the shade-roller 4. In Fig. 2, I have shown the device applied to another form 85 of window-case molding, 15, having a prominently projecting rib, 16, along its outer edge. With such a molding, the attaching-bracket may consist of both bracket-plates, 7 and 8, as shown in Fig. 1, the same 90 being more widely separated to receive the thicker molding, or it may consist of the outer plate, 7, alone, attached directly to the outer edge of the window-case molding by screw 17. In either case the slotted bearing-bracket, 3, is mounted upon the attaching-plate, 7, in reversed position, with its bearing-end projecting inward, as shown in 95 Fig. 2, in which position the bearing-aperture, 13, in said bearing-bracket is adapted 100 to receive the trunnion or spindle of the shade roller 4. By thus reversing the bearing-bracket, the shade-roller can be supported in proper relation to the face of the window-casing, whether the window-case 105 molding is of the ordinary form and thickness, or whether it is provided with the heavy ornamental rib or bead along its outer edge.

If desired, the inner angle-plate, 8, can be 110 reversed to extend outward from the window-case molding along the wall, and be

secured to the wall by nails or screws inserted through the apertures, 14, therein, as shown in Fig. 5.

What I claim as new and desire to secure by Letters Patent is—

1. A shade-fixture comprising an attaching-bracket adapted to be mounted upon a window-casing and having an arm adapted to project in front of the window-case molding, an angular bearing-bracket having a shank reversibly and adjustably secured to said attaching bracket, the bearing end of said bearing-bracket being provided with a plurality of bearing-apertures in substantially the same horizontal line at different distances from said shank adapted to interchangeably receive a shade-roller in substantially the same position in either reversible position in which the bearing-

bracket is mounted upon the attaching-bracket.

2. The combination with a window-casing having a case-molding; of a shade-fixture comprising a pair of angle-plates, one attached back of said molding and the other extending in front of said molding, said angle-plates having mutually lapping members adjustably connected together by screw-and-slot mechanism at the outer edge of said molding; and a shade-roller bearing-bracket mounted upon the front angle-plate.

In testimony whereof, I have hereunto set my hand this 27th day of January, 1912.

IRVING M. FLANAGAN.
